UNITED STATES PATENT OFFICE.

WILLIAM J. LANE, OF POUGHKEEPSIE, NEW YORK.

DOOR-HANGER.

SPECIFICATION forming part of Letters Patent No. 368,478, dated August 16, 1887.

Application filed August 4, 1886. Serial No. 209,990. (No model.)

To all whom it may concern:

Be it known that I, WILLIAM J. LANE, of Poughkeepsie, in the county of Dutchess and State of New York, have invented a new and 5 useful Improvement in Door-Hangers; and I do hereby declare that the following is a full, clear, and exact description of the same.

My invention relates to door-hangers, and is an improvement upon Letters Patent granted 10 to me on the 8th day of April, 1884, No. 296,584.

The object of the present invention is to produce a hanger of few parts, economical to make, and of increased strength.

15 It consists of hanger-ways formed of bar iron or steel, with their ends connected by separate pieces bent in approximately U shape, with the ordinary support, adapted to be attached to the door.

20 In the drawings, Figure 1 represents a perspective view showing my hanger attached at the top of a door. Fig. 2 is a plan view of the hanger. Fig. 3 is a vertical section through the hanger, showing it attached to the lower 25 portion of the door.

The hanger-ways are composed of bar-iron or steel of equal length, arranged parallel to each other, with a space between, in which the ordinary wheel travels. The ends of the ways 30 are connected together by connecting-pieces b b, bent approximately in U shape and riveted to the ends of the ways upon the outside thereof, so as to leave an unobstructed passage between the ways for the passage of the 35 wheel. The bent connecting-pieces b b are of a greater width than the hanger-ways, and being placed with their sides in planes parallel with the bearing-edges of the ways they form abutments above and below the same upon each

40 side, as shown, and as the wheel reaches one end or the other of the ways the axle of the wheel comes in contact with these abutments, which thus act as stops while the forward part of the wheel runs into the bend.

45 The connection for the door is shown as a U-shaped strap, as in my aforesaid patent, and the ends are riveted to the hanger-ways and to the connecting bent pieces by a rivet passing through the three thicknesses, as clearly 50 shown. It will thus be seen that by this con-

struction an exceedingly simple and strong construction of hanger is provided, all the parts being free from excessive strain, increased stiffness resulting from the simple arrangement of the parallel hanger-ways and the bent connecting-pieces at the ends, the abutments formed by the increased width of the bent connecting-pieces serving not only as a stop, but as they extend down on both sides they keep the wheel in line. This construction of hanger is also adapted for use upon the top or upon the bottom of the door, and no change is necessary in the construction of the hanger, as hereinbefore described, to adapt it to this change of location.

It is apparent that if a stop were desired only on the upper edges of the ways, or only on the lower edges, the edges of the wider bent end pieces could be made flush with one edge of each way; but this would not serve for a reversible hanger, and I therefore project the edges of the bent end pieces on both sides above and below; but I do not limit myself to the projection on both edges.

The hanger herein described differs from the 75 hanger shown in an application filed by me on the 10th day of April, 1886, No. 198,465, in this, that the ends of the way in that case are connected to each other by bending laterally the bars which form the ways, and thus forming the ends of the same depth as the ways, so that there is in that case no stop on one side, while, as above explained, the hanger now claimed is formed at the ends of the ways by bent pieces of greater depth than the hanger-ways and project to form an abutment or stop against which the axle of the wheel comes in contact.

I do not, therefore, herein broadly claim a door-hanger consisting of hanger-ways formed 90 of a bar or bars arranged with the larger axis in vertical planes with lateral bends at the ends of the ways, in combination with vertical supports attached thereto.

I claim as my invention—

A door-hanger consisting of ways composed of side bars arranged parallel to each other, with a space between for the wheel, bent end pieces, b, of material wider than the bars at each end, with their sides parallel with the bear- 100

ing-edges of the side bars and forming abutments for stops, said bent end pieces being riveted to the side pieces, and a strap or connection for attachment to the door, also riveted to the side bars, the parts being constructed and combined substantially as described.

In testimony whereof I have signed my name to this specification in the presence of two subscribing witnesses.

WILLIAM J. LANE.
